(57) **CLAIM**

I claim the ornamental design for an ignition gun, as shown and described.

DESCRIPTION

FIG. 1 is a perspective view of an ignition gun, according to the claimed design;

FIG. 2 is a front view of the ignition gun of FIG. 1;

FIG. 3 is a rear view of the ignition gun of FIG. 1;

FIG. 4 is a right-side view of the ignition gun of FIG. 1;

FIG. 5 is a left-side view of the ignition gun of FIG. 1;

FIG. 6 is a top view of the ignition gun of FIG. 1; and,

FIG. 7 is a bottom view of the ignition gun of FIG. 1.

The broken lines in the drawings depict portions of the ignition gun that form no part of the claimed design.
